UNITED STATES PATENT OFFICE.

CLYDE LEE MANON, OF FITZGERALD, GEORGIA.

COMBINATION-LOCK.

1,351,484.

Specification of Letters Patent. Patented Aug. 31, 1920.

Application filed January 28, 1919. Serial No. 273,604.

To all whom it may concern:

Be it known that I, CLYDE L. MANON, a citizen of the United States, residing at Fitzgerald, in the county of Ben Hill and State of Georgia, have invented certain new and useful Improvements in Combination-Locks, of which the following is a specification.

The present invention relates to improvements in combination locks, designed especially for use in connection with safes, vaults etc.

The primary object of the invention is the provision of a simple, but effective, locking device for this purpose which may be adjusted with facility, and operated with despatch; and is simple both in its construction and operation.

In the accompanying drawings I have illustrated one complete example of the physical embodiment of my invention constructed and arranged according to the best mode I have so far devised for the practical application of the principles of my invention.

Figure 1 is a front view in elevation of a safe equipped with my invention.

Fig. 2 is an enlarged, fragmentary view of the combination setting knobs and indications.

Fig. 3 is a front view of the operating parts of the invention, the bolts unlocked, as in dotted lines of Fig. 1.

Fig. 4 is a vertical transverse sectional view, taken on line 4—4 of Fig. 5.

Fig. 5 is a view, in reverse, of parts in Fig. 3.

In the preferred embodiment of the invention as shown in the drawings I have utilized a well known type of safe indicated at 1, having the usual door 2 hinged at 3, and the customary rollers or wheels 4 are indicated. The bolt-shifting knob 5 and the two knobs 6 and 6' for setting the tumblers or latches of the device, project from the front face of the door, and are located approximately in the positions indicated.

The mechanism is located in a chamber provided for the purpose in the door, and the door is of the usual metal and packing construction. I have illustrated, dotted lines Fig. 1, three bolts 7, adapted to engage the sockets 8 in the wall of the safe, and the bolts are connected to and integral with a vertically extending bar 9, the whole being movable in a vertical slot or space 10, in the door. The bolts, which are shown unlocked, are actuated through the knob 5 and its

spindle 11 which is rotatably supported as usual in the door, and the rock arm 12 on the spindle is connected to the bolt bar 9 by the link 13, loosely pivoted at 14 to the arm, and pivoted at 15 to the bar 9. Thus it will be evident that when the knob 5 is turned clockwise, the three bolts will be shoved into their sockets in the wall of the safe.

The latching mechanism for the bolts is also operated by this knob 5, through another rocker arm 16 on the spindle 11 which is connected to the stud or pin 17 at its bent end 17', the pin being secured to the pivoted link 18 as best seen in Fig. 4. The link 18 is pivoted on a pin 19 forming a fixed pivot and projecting from the bracket 20 that is secured within the chamber of the door.

It will be seen that the link 18 will be depressed when the knob 5 is turned to the right. At 21 on the end of this link is loosely pivoted a depressible bar 22, having a pair of guide carriages 23, 24 whose wheels are designed to travel on the guide rod or bar 25 fixed at 26, 26 to the interior walls of the door, thus providing for a reciprocal motion of the bar 22, with little friction.

The depressible bar is provided with a pair of fixed detents as 27 and 28 projecting therefrom in oblique lines and adapted to co-act with the respective sets of latches 29 and 30. For convenience I have illustrated and described two sets of latches, 29 and 30, and it will be evident that a larger number may be used, or even only one set of latches may be utilized if desired. These sets are made up of five latches each, all of which are designated by the number 31, and they are all rotatable or swiveled on their journal bars 32, 32 that are fixed in or supported from the two carriers 33, 33, springs 34 being fixed to the latches and bearing against the carriers 33, in order to normally hold the latches in position indicated in Fig. 4, in which certain latches engage the detents 27 and 28 and serve to hold the bar 22 in elevated position.

The two sets of latches are movable laterally for "setting" the combinations, and they are guided and supported in their movements along the guide bars 35 and 36, which are attached at their ends 37 to the door and extend transversely thereof. Each carrier 33, 33, is provided with two pairs of guide rollers 38, which travel over the horizontal guide bars and hold the latches in

position, while each carrier has a supporting arm 39 at each end thereof to which the bars 32 are fixed.

All of the latches or tumblers 31 are identical in shape and size, and each is formed with a single notch 41 at its free enlarged end or head and a cam face or edge 40 is also provided, against which the detents 27 and 28 of the depressible bar 22 are adapted to engage.

10 The latches are held in locked position by means of a frame or keeper 42 which is a rectangular, metal frame having lower transverse bar 43 and the intermediate bar 15 44 adapted to co-act with the respective sets of latches 30 and 29, each bar being adapted to engage one latch only of its set, *i.e.* the latch selected in the combination which is set up in each case. The latch frame or keeper is adapted to have a vertical reciprocal movement, and is guided in its movement by any suitable means such as the guide lugs 45 traveling in suitable grooves 45' indicated in dotted lines, in the walls of 20 the chamber.

25 At 46, the upper cross bar of the latch frame is slotted to receive the end of a lifting arm 47 pivoted at 48 on a bracket 48' forming part of the bracket 20 and the other end of this lifting arm is loosely pivoted on the pin 21 of the link 18. As indicated by the dotted lines and arrows, as the depressible bar 22 is depressed, the latch frame 42 is lifted, the movements bearing definite relation to one another as presently described. The bar and frame are so arranged in their movement that as the bar is depressed, contact of detents 27 and 28 with the cam faces 40 of certain of the latches 30 force the said latches to swing on their journals 32 in the direction of the arrows to the dotted line position of Fig. 4, and the movement of the frame is so timed that it is lifted to bring the lower bar 43 and the intermediate bar 44 into the notches 41 of the latches so shifted. In this manner the selected latches are brought to position where the frame may lock them in inactive position, after which, by sliding the sets of latches back to the zero points, the arm 22 will be prevented from raising by the other latches still in active position, thus locking the bolts 7 against withdrawal. To open, it is necessary to first again shift the sets 40 of latches through the knobs 6, 6' until those latches previously locked in inactive position, as just above described, are again opposite the detents 27 and 28 of the member 22 so that the latter may be raised as the bolt throwing handle 5 is manipulated to withdraw the lock bolts 7, it being obvious that the respective latches will be released by the frame 42 immediately upon the passage of the detents 27 and 28, thereby so 55 that the parts may again assume the posi-

tion shown in Fig. 4. In other words, in the present arrangement a member is provided which is depressible when the lock bolts are thrust into the locked position together with certain means to prevent the 70 said depressible member from being again elevated and the last mentioned means being selective to the extent that certain of the latches constituting the same may be shifted and secured in inactive position, so that the 75 depressible member is thus given a path of elevating movement, through the series of latches, although it requires that the latches shall be again shifted, in releasing the lock, to the same position they occupied 80 when the lock was secured.

In setting the combination, the latch to be engaged by the latch frame is selected through the medium of the knobs 6 and 6', and the journal bars 32 of the latch sets are 85 fashioned at their ends into rack bars 49 and 50 which are engaged by the respective toothed segments 51 and 52 on the spindles 53 and 54 of the respective knobs 6 and 6'. The knobs have the arbitrary designations 90 10, 20, 30, 40, 50 and five corresponding lines equaling the number of latches in each set, and these lines of course co-act with the indicator mark for each knob. In the drawings, in the upper set of latches, the middle 95 latch, or the latch corresponding to "30" has been selected, and in the lower set the second latch "20" has been selected. The latch sets are so positioned and supported on their guide bars 35 and 36, that when the 100 sets are at their extreme left positions in Fig. 5, the mark 10 will be at the right of the indicator mark, or at the left thereof, as desired, but the space for the sets to move in is sufficient of course to allow the required 105 movement of the sets. Thus, when the knob 6' is moved to position for 10 to register with the indicator mark, the first latch at the left in the sets will be brought, through the action of the segmental rack and rack 110 bar, into line with the depressible bar 22. Then, as shown in dotted lines in Fig. 1, when the knob 5 is turned, the bolts are shoved into their sockets, the two latches are moved by their cams and the frame with 115 its latch bars are brought to position to hold the latches through engagement with their notches 41. By giving the knobs 6 and 6' a slight turn the latch sets are moved so that the cam bar may be out of register with the 120 selected latches.

In Fig. 4 the device is shown unlocked. When locking the device the two knobs 6 and 6' are set on corresponding numbers, say 10 and 10, then turn knob 5, which 125 draws bar 22 with cam arms or detents 27 and 28 downward over cam faces 40 and 40. When the detents 27 and 28 are approximately two thirds over the latches 10 and 10 the keeper bars 43 and 44 are drawn to the 130

edges of notches 41 and 41 by the lifting arm 47 and as the detents pass over the latches the keeper bars are seated in the notches. The knobs 6 and 6' are then turned back leaving the latches 10 and 10' down in inactive position and four other latches in each set are left up into bar locking position.

5 What I claim is:—

1. The combination with a set of laterally movable revoluble latches and means for adjusting the latches to selected position, of a depressible bar adapted to engage a selected latch, a liftable keeper frame adapted to engage the selected latch, and means combined with locking mechanism for actuating said mechanism, the depressible bar and the keeper frame.

10 2. The combination with a series of latches, a guide rail and a carrier for said

latches supported on said rail, means for actuating the latches, a keeper for holding a selected latch, and means for moving a selected latch for engagement with the actuating means.

15 3. The combination with a locking bolt, 25 its spindle, and actuating mechanism between the spindle and bolt, of a plurality of sets of latches each latch provided with a notch and revolvably supported, means for adjusting each set to selected position, a 30 depressible bar for moving a selected latch in each set, a keeper frame having a keeper bar for each selected latch, and means actuated from the spindle for operating said cam bar and keeper frame, as described. 35

In testimony whereof I affix my signature.

CLYDE LEE MANON.
